OIL BURNING HEATER FOR TOBACCO BARN

Joseph Cabel Love and Chalmers Glenn Love,
Kenbridge, Va.

Application April 28, 1953, Serial No. 351,534

2 Claims. (Cl. 126—93)

This invention relates to an oil burning heater, particularly designed for heating tobacco barns in the flue curing of tobacco, although obviously it is applicable to other uses.

One of the objects of the invention is to provide a heater of the type indicated, equipped with a door, the opening of which releases the movable parts of the heater which from time to time require servicing, so that these parts can readily be removed without the use of tools.

Another object of the invention is to provide an oil heater as described, in which the mouth of the main air duct vertically overlies the oil distributor and vaporizer element of the burner, the inlet end of said duct extending through the front of the heater outside of the barn, so that there is no back pressure as in the case where air is derived from within a barn having inadequate openings to atmosphere, resulting in improved combustion.

A further object of the invention is to provide a massive burner comprising a bowl component and an oil distributor and vaporizer fitting said bowl component, there being means for providing an annular starting flame circumferentially of said burner in contact therewith in an intermediate zone, for heating the burner to change the liquid oil supplied thereto to vapor which is burned at the periphery of the oil distributor and vaporizer and beneath the mouth of the air intake duct.

Still another object of the invention is to provide an oil overflow at the forward end of the casing of the heater, and a dam across said casing rearwardly of the burner, extending to a higher level than said overflow, to prevent overflowing oil from running into the conduit for the effluent products of combustion where it would be a definite fire hazard.

Other objects of the invention will appear as the following description of a preferred and practical embodiment thereof proceeds.

In the drawings which accompany and form a part of the following specification, and throughout the figures of which the same reference characters have been used to denote identical parts:

Figure 1 is a side elevation of an oil burning heater embodying the principles of the invention;

Figure 2 is a front end view;

Figure 3 is a vertical longitudinal section through the heater, along the line 3—3 of Figure 2;

Figure 4 is an enlarged sectional view taken along the line 4—4 of Figure 3, viewed in the direction of the arrows;

Figure 5 is a diametrical cross-section taken along the line 5—5 of Figure 3.

Referring now in detail to the several figures, the numeral 1 represents the cylindrical body or casing of the heater, which is horizontally disposed. Said casing is supported between the bifurcations 2 and 3 of front and rear supports 4 and 5, forming parts of the integral base 6.

The casing 1 is divided in a horizontal axial plane. Each half has the outwardly extending flanges 7 and 8 secured together by bolts 9, through which the halves of

2

the casing are joined together. The flanges 7 and 8, as shown, terminate a short distance from the front of the casing and a greater distance from the rear thereof. The rear portion 10 of the casing is tapered, a bead 11 being provided at the inner or wider end of the tapered portion. The heating conduit 12 a part of which is shown in Figure 1, is slipped over the tapered portion 10 as far as the bead 11, or in any event, until it makes a tight fit with said casing.

The upper part 13 of the casing is formed at the front with an outstanding semicircumferential flange 14, and said upper part is closed at the front by means of a semicircular door 15, having a semicircumferential channel 16 at its rear, which freely hooks over the flange 14. The door has a forwardly projecting handle 17 and is removed by grasping the handle and raising the door vertically so as to clear the flange 14.

The lower part 18 of the casing is provided with an integral semicircular front end 19 which is in the same vertical plane as the door 15. Said door and the front end 19 are formed with matching semicircular recesses 20 and 21 which together form a circular hole 22 (see Figure 2). The meeting edges of the front end and door, including the periphery of the semicircular recesses 20 and 21 are faced by outwardly extending strengthening flanges 23 and 24.

The lower part 18 of the casing 1 is integrally formed with the massive bowl component 25 of the burner, which is formed with a cylindrical oil preheating chamber 26, to which oil is supplied through the conduit 27. Above the chamber 26 the bowl component 25 is provided with an expanded vaporizing chamber 28. Above said vaporizing chamber said bowl component is formed with a bowl of frusto-conical shape, the flared walls 30 of which form a seat for a freely inserted oil distributor and vaporizer 31, having a series of circumferential grooves 32 formed in its outer periphery, communicating with the vaporizing chamber 28 at one end, and with the general chamber of the casing 1 at their upper ends. The oil distributor and vaporizer has a centrally located upstanding tit 33, which as shown, is of square cross-section.

A capacious air inlet duct 34 of elbow shape has its outer end 35 passing through the hole 22 in the front of the casing, and is provided with a cross bar 36 at its inner end, having a central recess 37 of complementary shape to the end of the tit 33, which receives the tit so that the weight of the air inlet duct holds the oil distributor and vaporizer in place and the oil distributor and vaporizer including the tit, allocates and secures the air inlet duct.

The conduit 27 extends between the front bifurcations 2 and 3 of the base, parallel to and in adjacency to the lower part 18 of the casing, so that when the latter becomes heated, heat is imparted to the conduit 27 by radiation as well as by conduction directly from the bowl component 25, so that the oil in the conduit 27 is preheated. In order for the oil to acquire as much heat as possible, the conduit 27 is of relatively large diameter so as to retard the velocity of the oil passing through said conduit. A smaller pipe 38 leading from an oil supply, not shown, and provided with a cut-off valve 39, is connected to the conduit 27.

The bowl component 25 is provided with a stepped annular lower portion 40, having a channel 41 in its upper face, containing an annular asbestos wick 42. The front end 19 of the lower part 18 of the casing is provided with an overflow pipe 43 as a somewhat lower level than the channel 41, said overflow pipe leading to a suitable sump, not shown, provided with means, not shown, such as a float controlled pump, which returns the overflow from the sump to the oil supply. The front end 19 is also provided with a series of auxiliary air inlet openings 44, communicating with atmosphere.

The lower part 18 of the casing, at a point rearward of the burner, is provided with an integral dam 45 extending thereacross, having a horizontal top edge which is at a higher level than the overflow pipe 43.

The operation of the heater is as follows. With the parts in the position shown in Figure 3, the cut-off valve 39 is opened and oil supplied to the burner which passes through the groove 32 of the oil distributor and vaporizer and flows into the channel 41, saturating the wick 42. Any excess oil overflows into the bottom of the lower part of the casing 18, and is discharged through the overflow pipe 43. The burner is lit by removing the door 15 and applying a match to the asbestos wick 42. Presently the bowl component 25 becomes sufficiently heated to vaporize the oil in the chamber 28 and grooves 32, the oil vapor being ignited by the lit asbestos wick. Air to support combustion is drawn in through the air inlet duct 34 and through the auxiliary air inlets 44. The down draft of air upon the top of the oil distributor and vaporizer spreads the flames out into the general chamber of the casing, producing intense and complete combustion. Since the air through the duct 34 is drawn from atmosphere outside the barn, it will not be subject to back pressure, as would be the case if it were drawn from the barn atmosphere, a more free flow of air being thus assured, with improved combustion. The dam 45 precludes the possibility of any of the overflow oil at time of starting entering the heat conduit 12 and thus producing a fire hazard within the barn.

It is frequently necessary to service the parts of oil heaters which are associated with the burner and air inlet passages, for the removal of soot. This is readily accomplished in the present construction without the use of tools. It is simply necessary to remove the door 15; then the air inlet duct 34 can be lifted from the oil distributor and vaporizer and removed through the door opening and the oil distributor and vaporizer can be lifted out by taking hold of the tit 33. When the parts are reassembled, the air inlet duct remains firmly in place, even when the door is removed, since it fits the recess 21 in the front end 19, and the interdigitating tit 33 and recess 37 form a "sticking" taper. In the servicing of the burner it is sometimes necessary to clear the interface between the oil distributor and vaporizer and the bowl component 25. This is done by rotating the oil distributor and vaporizer against its seat in the component 25, which is readily accomplished by grasping the square tit 33.

While we have in the above description disclosed a practical embodiment of the invention, it will be understood by those skilled in the art that the specific details of con-

struction and arrangement of parts, as shown, are by way of example and not to be construed as limiting the scope of the invention.

What we claim is:

1. An oil burning heater comprising a casing constituting a horizontally extending combustion chamber, a closure at one end, the opposite end having an opening adapted for connection to a discharge flue, said closure being divided horizontally into upper and lower parts, the lower part being fixed and the upper part being formed with the matching halves of a circular hole and with matching flanges bordering said hole extending outwardly therefrom, a burner within said casing comprising a body having a circular chamber with an upwardly flaring conical surrounding wall opening in the upper face of said body and being connected to a source of liquid fuel, a removable oil distributor and vaporizer having a peripheral seating wall of a shape complementary to said flared wall and seated upon said flared wall, an elbow shaped air duct freely mounted in said casing having a horizontal limb extending slidably between said matching flanges in gas tight engagement therewith, said air duct having a vertical limb overlying said oil distributor and vaporizer and having a cross bar at its inner end, said cross bar and oil distributor and vaporizer being formed with freely separable snugly interfitting means aligning said oil distributor and vaporizer coaxially with said vertical limb and supporting the latter, the horizontal limb of said air duct being supported by the fixed part of said closure and held in position by said door.

2. An oil burning heater as claimed in claim 1, said casing and door at the top being provided with freely interhooked flanges for detachably securing said door in closed position.
